UNITED STATES PATENT OFFICE.

JOSEPH GODFREY VICHE, OF DULUTH, MINNESOTA.

TOE-BOARD.

1,139,240.

Specification of Letters Patent. Patented May 11, 1915.

Application filed December 13, 1913. Serial No. 806,637.

To all whom it may concern:

Be it known that I, JOSEPH GODFREY VICHE, a citizen of the United States, residing at Duluth, in the county of St. Louis 5 and State of Minnesota, have invented new and useful Improvements in Toe-Boards, of which the following is a specification.

This invention relates to gang ways of that class which are used particularly to 10 provide a passage way for a two wheel truck in transferring merchandise from one railroad car to another, said gang ways being usually known as toe boards.

The invention has for its object to produce a device of this class which shall be 15 simple in construction, durable and the construction of which shall be such that there will be no vertical vibration due to the passage of a truck thereover which would tend 20 to dislodge the toe board as well as the truck.

A further object of the invention is to produce a toe board having guard flanges at the sides thereof to prevent the possibility 25 or likelihood of the wheel trucks passing over the edge of the board.

A further object of the invention is to produce a toe board of arcuate shape having upstanding corrugations or ridges which 30 constitute wheel guards and which also when the board is inverted will constitute runners to permit the board to be conveniently dragged from place to place.

With these and other ends in view which 35 will readily appear as the nature of the invention is better understood, the same consists in the improved construction and novel arrangement and combination of parts which will be hereinafter fully described 40 and particularly pointed out in the claims.

In the accompanying drawing has been illustrated a simple and preferred form of the invention, it being, however, understood that no limitation is necessarily made to the 45 precise structural details therein exhibited, but that changes, alterations and modifications within the scope of the claims may be resorted to when desired.

In the drawing,—Figure 1 is a top plan view of a toe board constructed in accordance with the invention. Fig. 2 is a longitudinal sectional view of the same taken on the line 2—2 in Fig. 1, and showing a truck in position thereon. Fig. 3 is a transverse 55 sectional view taken on the line 3—3 in Fig.

1. Fig. 4 is a sectional detail view on an enlarged scale taken on the line 4—4 in Fig. 1.

Corresponding parts in the several figures are denoted by like characters of reference. 60

The improved toe board is made of a single sheet of metal such as boiler steel of suitable gage, said sheet being of any desired dimensions and of rectangular shape. The sheet, which is designated by 15, is bent 65 to arcuate form, as best seen in Fig. 2, and ribs or corrugations 16 are formed longitudinally thereof and adjacent to the sides thereof, said ribs or corrugations which are likewise arcuate or rocker-shaped being upstruck from the material.

It will be noticed that the arcuate rocker-shaped ribs 16 are of a smaller radius than the sheet 15 and that consequently when the said sheet is overturned, as will be presently 70 hereinafter described, only a limited portion of said ribs will engage the surface of the ground. It is obvious that these ribs or corrugations will not only reinforce the arcuate sheet against yielding or bending 75 downwardly intermediate the ends thereof, but that said ribs will also constitute guards to prevent the wheels 17 of a truck 18 that is wheeled over the board from accidentally passing over the side edges of the board. 80

The sheet 15 is provided adjacent to the end edges thereof with threaded apertures 19 for the reception of calk members C, each of said members comprising a peg or prong made of steel and having a sharp pointed end 20, a threaded shank 21 and an annular flange 22 intermediate the ends thereof, said flange being of non-circular shape so as to constitute a wrench seat to enable the calk to be conveniently applied 85 or detached. These calks, any desired number of which may be used adjacent to each end of the toe board, will serve to engage

the wooden floors of the cars, the space between which is bridged by the toe board, thereby preventing accidental displacement of the latter. The toe board is also provided adjacent to each end edge with an aperture 23 which may be engaged by a hook or the like for the purpose of handling the toe board and dragging it from place to place. 90

When the improved toe board is in use, it is placed convex side uppermost in position to bridge the space between adjoining 100

105

110

freight cars, and it will be held securely in place by the calks C engaging the floors of the cars. When trucks are wheeled over the toe board, the upstanding ribs 16 will serve as wheel guides or guards to prevent the wheels running over the edges of the board. The said ribs also constitute reinforcements that will prevent the board from yielding downwardly to any appreciable extent. Furthermore, when it is desired to move the board from place to place it is simply inverted, and the arcuate ribs will then engage the ground and constitute rocker-shaped runners. When a drag rope, a hook or the like is engaged with one of the apertures 23 the board may then be rocked to elevate the portion nearest the operator who is thus enabled to drag the board over the ground from place to place, there being little or no frictional resistance because only a very limited portion of the ribs 16 will at any time be in ground engaging position.

Having thus described the invention, what is claimed as new, is:—

A toe board consisting of a rectangular sheet of metal curved longitudinally and having upstanding rocker-shaped ribs of smaller radius than the curvature of the sheet on the convex side adjacent to the side edges thereof, said ribs constituting reinforcing braces, wheel guards and, when the toe board is overturned, runners for convenience in moving the device, the curvature of said runners being such that only limited portions thereof may at any time be in ground engaging position on a level surface.

In testimony whereof I affix my signature in presence of two witnesses.

JOSEPH GODFREY VICHE.
